(57) **CLAIM**

The ornamental design for a charging case for sleep-inducing earbud as shown and described.

DESCRIPTION

The patent or application file contains at least one drawing executed in color. Copies of this patent or patent application publication with color drawing(s) will be provided by the Office upon request and payment of the necessary fee.

1. Charging case for sleep-inducing earbud

1.1 : Front perspective view

1.2 : Bottom perspective view

1.3 : Front

1.4 : Back

1.5 : Left

1.6 : Top

1.7 : Bottom

1.8 : Reference view

The broken lines shown in the reproductions depict portions of the charging case for sleep-inducing earbud that form no part of the claimed design; a right view is omitted because it is a mirror image of the left view; reproduction 1.8 shows a product in state of use with the lighting illuminated and forms no part of the claimed design.
